YARN TAKE-UP DISK FOR DOUBLE TWIST SPINDLES

John Kermit Cochran, Conyngham, Pa., assignor to The Duplan Corporation, Hazleton, Pa., a corporation of Delaware

Application February 14, 1948, Serial No. 8,346

5 Claims. (Cl. 57—58)

1

This invention relates to the storage ring or takeup disc of double twist spindles for spinning or twisting textile yarns.

In the type apparatus referred to, yarn from a supply spool or package passes downwardly through a hollow spindle, then outwardly through a transverse outlet passage near the lower end of the spindle blade or shank. The yarn then passes around a takeup disc and upwardly over a guide to a rotating takeup spool or package usually located above the rotating spindle. Since the spindle is rotating, the primary twist is inserted in the yarn between the supply package and the spindle outlet, and the secondary twist occurs between the spindle outlet and the takeup spool.

Variable tensions which the yarn undergoes in the twisting operation, have been a problem in the industry. Attempts have been made to provide apparatus which will overcome the varying tension problems, but the solutions were applicable only to a particular yarn size or weight. Other attempts to overcome the problem for general purposes have been commercially unsuccessful, as will be apparent after the nature of the problem is more fully explained.

A great many variables act on the yarn during the twisting operation, creating variable tensions at different points. For instance, different yarn weight or different physical characteristics of the yarn, such as the texture, affect the tension which occurs in the balloon; also wind resistance of the balloon has a definite effect on the tension. Additionally, of course, the speed at which the yarn is twisting and taken up on the takeup reel, affects the tensions undergone by the yarn; also, at the supply end, the tension varies as the amount of yarn on the supply package decreases. Furthermore, slight imperfections in the wind or build of the supply package create variable instantaneous tensions as the yarn is drawn away from the supply package.

In the course of study of the various tensions which are encountered by the yarn, it has been found that they may roughly be divided into two groups, constituting what might be referred to as primary tension and secondary tension. The primary tension occurs between the supply package and transverse outlet of the spindle, and the secondary tension between the transverse outlet and the takeup spool. In operation, if the primary tension is too great, then the yarn will twist apart or break. If, on the other hand, the secondary tension is too great, the yarn will become overstressed and may break.

2

Numerous attempts have been made to design a spindle so that it will compensate for variations in primary tension without changing secondary tension. For instance, a flier arrangement, located between the supply spool and the top of the spindle, has been provided, in which the yarn passes through a loop which is supported by a bearing mounted on the top of the spindle assembly and is rotated slowly by the unwinding of the yarn from the supply package. By careful adjustment of the friction of the bearing, the tension could be regulated so as to avoid trouble. However, since the diameter of a full package of yarn will differ from the diameter of a package which is almost exhausted by as much as two and a half times, the tensions will vary from point to point, and the snubbing action of the rotating flier does not compensate. Thus, the increased tension caused breakage when the package had been depleted by, for instance, half the original amount.

Proposed methods of overcoming this difficulty were to vary the friction of the flier periodically or to use spools or packages of yarn which contained only half the amount of a normal package, so that the difference between the diameter of a full package and that of an exhausted package was not great and, therefore, the resulting increase in tension was not sufficiently great to cause breakage of the yarn. Such arrangements, of course, are extremely undesirable and unsatisfactory from a commercial or production point of view.

Another arrangement was that of providing small fiber gears or discs rotating within the stationary part of the spindle, with one of the fiber discs exerting pressure on the other by means of a spring which was adjustable. The yarn passing through the spindle passed between the discs, and the rotating gears or discs were intended to control the variable tensions encountered by the yarn. Such an arrangement was, of course, difficult and expensive to manufacture commercially, and further suffered in that the spring controlling the small discs within the spindle required readjustment for different types or textures and sizes of the yarn, or the speed of operation. In commercial use, adjustment of the spring was extremely difficult.

Other attempts have been made to overcome the tension problems, such as, for instance, guides arranged so as to control the shape of the balloon, thus controlling the variations in tension. Such arrangements were extremely cumbersome and took up valuable and useful space, which, as

well understood by those skilled in the art, is a premium in the textile industry.

Therefore, it is the object of this invention to provide an effective yet simple solution to the varying tension problem encountered in throwing yarns, particularly in double twist spindles.

Another object is to provide a storage or take-up disc which will compensate for the various tensions encountered by the yarn in double twist spindles.

Further objects will be apparent to those skilled in the art after a study of the description, claims, and drawings—in which

Figure 1 is a sectional view of a double twist spindle assembly, showing the takeup disc and the manner in which the yarn passes through the spindle and to the takeup reel;

Figures 2 and 3 are bottom plan view and side elevational view, respectively, of a preferred construction of the takeup disc; and

Figure 4 shows a modified form of takeup disc, illustrating the yarn path principles.

In accordance with this invention, a means has been provided for storing in a spiral fashion the yarn as it leaves the outlet of the spindle. Heretofore the yarn, in passing from the spindle outlet upwardly over a guide, has passed around the takeup disc. Since the yarn emerged from an opening near the upper outer edge of the disc and passed upwardly toward the takeup spool, thus leaving the disc from the same upper outer edge, a complete encirclement of the disc meant that the yarn tended to overlap itself. Thus, it was desirable that the yarn pass only part-way around the disc before curving upwardly toward the takeup reel to avoid overlapping with attendant tendency to break.

The apparatus in accordance with this invention is illustrated in Figure 1, in which there is a double twist spindle blade 11 having a longitudinal opening 12 through which the yarn 13 passes. Near the lower end of the shank portion of the spindle, the outlet passage 14, extending transversely of the spindle, is provided.

Normally, a takeup disc 15 is fitted onto the spindle at the point opposite the outlet 14 thereof. The takeup disc may be of any desired construction, either a skeleton framework or a solid disc, having a path 16 around the outer edge thereof for the yarn. An opening 17 passes diametrically through the disc, connecting an axial opening 20 with the outer edge thereof, providing a continuous passage for the yarn as it leaves the outlet 14 of the spindle 11.

In the form illustrated, the circumference of the disc 15 provides a smooth and flat surface for the yarn as it passes around the periphery of the disc. The particular shape of the outer edge of the disc providing the path for the yarn, is not critical, however, and it will be apparent that different forms may be used.

A portion 18 of the disc, which may also be a separate piece, such as a die-cast rotor, if preferred, mounted on the lower end of the spindle just above the disc, serves as a guide for the yarn as it passes from the takeup disc to the takeup reel 19 located above.

A flir is provided at the top of the spindle assembly, consisting of a small bearing 21 which may be of wood, for instance. An elongated piece of wire having a loop 23 on the end thereof, is attached at one end to the wooden bearing 21 and extends radially. Loop 23 should preferably be at or slightly beyond the edge of supply package 10. In the actual construction, a second

duplicate wire, extending diametrically opposite the first, is provided as a matter of convenience in threading. The friction between the wooden bearing 21 and the assembly on the end of which the bearing is mounted, is not critical.

As may be seen, the yarn which is to be twisted passes in over end relationship from the supply spool 10 through the wire loop 23 downwardly through the hollow spindle assembly and outwardly through the spindle outlet 14 into the takeup disc opening 17. At the beginning of the operation, the yarn passes directly upwardly over the rotor guide 18 to the rotating takeup reel 19. Another guide may be located near the takeup reel, if desired. As the spindle begins to rotate, the yarn is pulled out from the opening 16 and it balloons outwardly and upwardly, as indicated at 24. When this occurs, the yarn begins to wind itself around the takeup disc 15.

20 In accordance with this invention, the yarn emerges from the opening 17 in the disc 15 at a point at the lower edge of the disc. In order that this outlet point for the yarn may be at the lower edge of the disc, there is provided, in accordance with this particular embodiment of the invention, a horizontally extending pin 25 passing across the opening in the lower half thereof. Vertical pins 26 are inserted near the opposite edges of the opening 17. These pins provide a smooth surface over which the yarn may pass in emerging from the opening 17 around the edge of the disc 15. When the yarn is threaded before the operation begins, it is brought out of the point indicated so as to emerge from the opening 17 at the lower half of the flat edge 16 of the disc. The yarn is then threaded upwardly to the takeup reel 19.

With this arrangement, as the rotating spindle 11 picks up speed, the yarn will wind itself spirally upwardly around the disc 15 as it passes upwardly to the takeup reel 19. In other words, while the yarn leaves the circumferential path or surface 16 of the disc 15 at the lower edge thereof and wraps itself around the disc, it leaves the side of the disc at the upper edge in passing upwardly to the takeup reel. This is illustrated in Figure 4. With this arrangement, the yarn may wrap itself around the disc several times without overlapping itself because of the spiral positioning of the yarn on surface 16.

50 While a particular arrangement for guiding the yarn out of the opening 17 near the lower part of the edge of the disc 15 has been described and illustrated, it is obvious that many variations are possible. For instance, a small passage may be bored diametrically through the disc with the outer opening 17' thereof near the lower edge of the circumferential side of the disc, as illustrated in Figure 4. In this way, the yarn would emerge near the lower edge of the disc; also, the opening 17 could be covered, leaving a small hole near the lower side of the opening so that the yarn would emerge near the lower edge of the disc 15. Other variations are possible in which a path on 55 a surface will be provided for multiple turns of yarn wound on said surface in a spiral manner. Thus, the particular structure illustrated and described represents merely one way of guiding the yarn from the edge of the disc at the desired point.

The arrangement described provides a snubbing action regulating the variable tensions involved in throwing yarns of various weights and textures at the speeds encountered. For instance, 60 as the spindle is set in motion after threading

the yarn will wrap itself around the smooth surface or path on the edge of the disc. As the secondary tension increases the number of turns will decrease, decreasing the snubbing action until equilibrium between the tensions has been reached. As the number of turns decrease the yarn is permitted to slide around the disc so that an increment of yarn is withdrawn until equilibrium is established. Similarly, if during the operation the primary tension should for any reason decrease the number of turns on the disc will increase, increasing the snubbing action. If, on the other hand, the primary tension increases, then the number of turns on the disc will decrease so as to decrease the snubbing action. In each case the number of turns will vary until equilibrium is established. Thus, the snubbing action of the spiral winding of the yarn about the take-up disc automatically adjusts itself to each of the variances in tension encountered.

It has been found that this arrangement greatly improves the snubbing adjustment for varying tensions encountered in spinning or twisting textile yarns. The automatic and immediate compensation provides an improved snubbing action to prevent undue tension at any point on the yarn caused by variables such as speed of operation, difference in yarn weight, difference in physical characteristic of texture of the yarn, and variation in the amount of yarn on the supply spool.

It will be apparent that this solution to the long standing tension problem is simple and economical.

While preferred embodiments of the invention have been described and illustrated, it will be apparent to those skilled in the art that modifications may be made without departing from the scope of the invention.

What is claimed is:

1. In apparatus for yarn spinning and twisting, a circular takeup disc having an axial opening, an outer circumferential edge providing a smooth flat path for multiple turns of yarn, an outer opening in said path, and an open passage extending radially connecting said axial opening with said outer edge, the edges defining said outer opening being located in the lower side of said path.

2. In apparatus for spinning and twisting textile yarns, a takeup disc having an axial open-

ing, a smooth surfaced outer side providing a flat path for multiple turns of yarn, an outer opening in said path, a yarn guide surface extending laterally from one edge of said path, and a radial passage connecting said axial opening with said outer opening in said path, the edges defining said outer opening being located at the edge of said path away from said guide.

3. In apparatus for spinning and twisting textile yarns, a takeup disc having a smooth surfaced outer side providing a flat path for multiple turns of yarn, an axial opening in said disc, a radial passage connecting said opening with said path, and smooth surfaced pins located in said passage providing in the lower half thereof, a bearing surface for said yarn in passing therethrough.

4. A yarn takeup disc according to claim 3, in which said pins comprise a plurality of pins parallel to the axis of said disc located near the outer opening of said passage, and a pin mounted normal to said plurality of pins and at the lower side of said opening.

5. Apparatus for spinning and twisting textile yarns comprising a spindle having a yarn takeup disc, said takeup disc having an axial opening and an outer circumferential edge providing a smooth surfaced flat path for multiple turns of yarn, and positive guide means for said yarn positioned at the lower side of said path whereby said yarn is led outwardly onto said path at the lower edge thereof to permit multiple turns of single layer spiral windings of said yarn on said disc.
